CLAIM

The ornamental design for a display screen with an animated graphical user interface, as shown and described.

DESCRIPTION

FIG. 1 is a first image of a sequence of a display screen with an animated graphical user interface showing our new design; and

FIG. 2 is a second image of a sequence of a display screen with an animated graphical user interface showing our new design.

FIG. 3 is a third image of a sequence of a display screen with an animated graphical user interface showing our new design; and,

FIG. 4 is a fourth image of a sequence of a display screen with an animated graphical user interface showing our new design.

The portions of the design shown in broken lines or dashed lines are included for the purpose of illustrating environment and form no part of the claimed design.

1 Claim, 4 Drawing Sheets
